United States Patent Office.

WILLIAM W. FINCH, OF MISHAWAKA, INDIANA.

Letters Patent No. 65,737, dated June 11, 1867.

IMPROVED MOP-WRINGER.

The Schedule referred to in these Letters Patent and making part of the same.

TO ALL WHOM IT MAY CONCERN:

Be it known that I, W. W. FINCH, of Mishawaka, in the county of St. Joseph, and in the State of Indiana, have invented new and useful improvements in Mop-Wringers; and do hereby declare that the following is a full, clear, and exact description thereof, reference being had to the accompanying drawings, and to the letters of reference marked thereon.

In the annexed drawings, making part of this specification, A represents a metallic frame, which consists of a single wire, bent in the form seen, with its ends connected together by means of a cross-bar, B. C is also a cross-bar, secured between the two side-pieces of the frame for a support or brace. D represents a rod, provided at one end with a handle, H, and at the other with a bar, E; said bar being secured at its centre to the end of the rod, and made forked at each end. The rod D passes through holes in the centres of the bars C and B made to receive it. The frame A is bent so as to be narrower at x x than it is the balance of its length. The bar E is made long enough so as not to touch the side-pieces of the frame, except at that point where the frame is made narrower, and at this point x x the frame sides fit snugly in the forked ends of the bar E, so as to prevent said bar from turning. F represents the mop-cloth, one end of which is secured to the lower end of the frame A, and the other end to the bar E.

When I wish to use the mop for washing and scrubbing I thrust the rod D down until the forked ends of the rod E catch on the sides of the frame at its lower end at x x . A spring, G, upon the handle H, catches upon the bar B, and keeps the rod D down in the proper position. When I wish to wring the mop-cloth I raise or loosen the spring, draw the rod D up so as to disengage it, and then, by turning it around and around, I twist the cloth so as to wring the dirty water from it.

Having thus fully described my invention, what I claim as new, and desire to secure by Letters Patent, is—

The forked bar E upon the end of the rod D, used in combination with the frame A, contracted at the end, in the manner and for the purposes specified.

In testimony that I claim the foregoing, I have hereunto set my hand and seal this eighth day of March, 1867.

WILLIAM. W. FINCH.
